Samuel W. Gibbs (assignor of A. Quackenbush) Albany, N.Y.
Letters Patent (Design No. 160) dated Nov 27 1847

The schedule referred to in these Letters Patent and making part of the same.

To all whom it may concern: Be it known that I Samuel W. Gibbs, of Albany in the County of Albany and State of New York, have invented or produced a new ornamental design for an air tight Parlor Stove, and I do hereby declare that the accompanying drawings are full and accurate delineations of a stove after my said design; the sides not shewn in the drawing being similar to, and symmetrical with, those represented.

That I claim as my invention and desire to secure by letters Patent is, the combination and arrangement of ornamental forms and figures forming respectively the top, bottom, and side plates; the whole forming an ornamental design for a parlor airtight Stove.
